UNITED STATES PATENT OFFICE.

WILLIAM H. MURPHY, OF LOWELL, MICHIGAN.

WHIFFLETREE-HOOK.

SPECIFICATION forming part of Letters Patent No. 403,364, dated May 14, 1889.

Application filed February 28, 1889. Serial No. 301,530. (No model.)

To all whom it may concern.

Be it known that I, WILLIAM H. MURPHY, a citizen of the United States of America, residing at Lowell, in the county of Kent and State of Michigan, have invented certain new and useful Improvements in Whiffletree-Hooks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in whiffletree-hooks.

The object of my invention is to provide means whereby the trace-hooks can be quickly and securely attached to the whiffletree-hooks, 2c without liability of becoming misplaced; and my invention consists in the construction and combination of the parts, as will be hereinafter fully set forth, and specifically pointed out in the claims.

25 In the accompanying drawings, Figure 1 is a perspective view of my improved whiffletree-hook, and Fig. 2 is a plan view.

A refers to a ferrule, provided with an open-ended box, b, the upper wall of which is provided with a key-hole slot, c. An eye or loop, d, is cast with the rear part of the ferrule, and through this loop passes and freely plays a ring, D, which has formed integral therewith a hook, E, the end of which is provided with a knob or ball of such a diameter that it may be passed through the opening in the upper wall of the open-ended box. The free end of this hook, upon which the ball or knob is formed, extends beyond the forward portion 35 of the ring D. It is proposed to make the ferrule of a single casting, the outwardly-extending walls and the eye d being all formed integral.

It will be observed that the front end of 45 the box b is open, so that the end of the hook will have free play therein, as well as a slight vertical movement, and in practice I propose to provide the eye d with a slotted opening to permit the ring to have a slight rearward

movement therein, so that when there is pressure upon the hook the ring will be drawn slightly forward and bear against the ferrule at the end of the whiffletree, so as to locate the ball on the end of the hook a slight distance in front of the enlarged portion of the 55 key-hole slot.

The ring D is of sufficient diameter to permit it to be swung over the end of the whiffletree.

To attach the trace-eye so that it cannot be accidentally detached, it is only necessary to pass it over the end of the hook and then swing the hook above the projecting plate or upper wall of the box, when it can be passed through the slot, when the trace will be securely maintained in position.

The hook and ring may be either formed of one continuous piece of metal; or the hook may be rigidly attached to the ring.

Having thus described my invention, what I claim as new, and desire to secure by Letters Patent, is—

1. The combination, with the ferrule A, provided with forwardly-extending walls, the upper wall being provided with a key-hole slot, 75 and a swinging hook secured to the ferrule, provided on its end with an enlarged portion adapted to pass through the key-hole slot to locate the end of the hook within the open-ended box, substantially as shown, and for 80 the purpose set forth.

2. The combination, with a ferrule having horizontal and vertical walls b, which project forwardly from said ferrule, the upper wall being provided with a key-hole slot, c, and a 85 swinging hook secured to the ferrule so as to encircle the end of the whiffletree, the end of the hook being extended rearwardly beyond the forward portion of the ring and provided with an enlarged end, substantially as shown, 90 and for the purpose set forth.

In testimony whereof I affix my signature in presence of two witnesses.

WILLIAM H. MURPHY.
